TRACK CIRCUIT FOR RAILROADS

Wade H. Reichard, Rochester, N. Y., assignor to
General Railway Signal Company, Rochester,
N. Y.

Application May 26, 1934, Serial No. 727,697

11 Claims. (Cl. 246—41)

This invention relates in general to track circuits such as used in railway signaling practice and has more particular reference to means for automatically discriminating between current changes in the track circuit due to the occupied condition of the track and due to leakage currents resulting from poor ballast conditions.

In railway operation it is quite essential that the usual track relay connected across the track section at one end of a signaling block be sufficiently energized when the block is unoccupied to pick up and hold up with certainty. It is likewise essential that the occupancy of the track section will so effectively shunt or condition the relay that it will be positively released. For example, in the usual track circuits if the normal holding current is too high, shunting may not be effective to drop the relay and if the normal holding current is so low that shunting will be more positive it is possible that at times the holding current may be insufficient.

Taking the above into consideration it will be seen that the usual variation in ballast resistance encountered in practice, due primarily to changes in weather conditions, may operate to interfere with the proper operation of the track relay unless some means is provided for discriminating between changes due to ballast resistance and track occupancy.

As the ballast resistance increases, the leakage current between the rails decreases so that the voltage across the terminals of the track relay connected to the track circuit increases. Conversely, as the ballast resistance decreases, ballast leakage increases and the terminal voltage at the relay decreases.

The relay current will vary over a considerable range and cover a range at times which will prevent proper response of the relay under occupied or unoccupied conditions of the track section.

It is proposed in accordance with this invention to provide means associated with the track relay for discriminating or detecting a change due to track occupancy and unoccupancy and changes due to leakage currents caused by variation in ballast resistance between the rails of the track. In accordance with the present invention it is proposed to improve the shunting efficiency of the track circuit and for this purpose a discriminating arrangement is included in the circuit of the track relay which discriminates between a slow change in track shunt due to track ballast and a rapid change in track shunt due to train occupancy.

55. Further objects, purposes and characteristic

features of the invention will appear as the description progresses, reference being made to the accompanying drawing showing by way of example one form which the invention may assume.

The single figure diagrammatically illustrates 5 one form of the present invention applied to a single stretch of track.

Apparatus.—Referring to the drawing, a section of railway track including rails 1 is shown separated from the adjacent track sections by 10 insulated joints 2. A track battery 1B and a limiting resistance R are shown connected to the track rails at the right hand end of the illustrated track section.

As typical of the control exercised by the track 15 relay, a semaphore signal SG is illustrated at the left hand end of the track section. A track relay T, having two coils is illustrated, the control of which will be explained in detail. A Pliotron or amplifier tube RC of any well known type is used, 20 and as illustrated, is adapted to control, by means of the voltage generated in the secondary of transformer TR, the current for operating selecting relay 1S.

Associated with Pliotron RC is the usual plate 25 source of current which may be a battery 2B and the usual filament source of current which may be a battery A. Bias resistor BR is adjustably connected to the grid circuit of the amplifier in order to provide a normal bias to the in-put of 30 the tube for a purpose that will be later described. Slow acting selecting relays 2S and 3S are provided and these relays in cooperation with relay 1S insert resistances 1R, 2R and 3R in the track circuit under certain conditions in a manner and 35 for a purpose that will be explained in detail.

Normal conditions.—With the circuit in its normal condition as illustrated in the figure, track relay T is normally picked up over a circuit extending from the (—) terminal of battery 1B, resistance R, lower track rail, lower winding and upper winding of relay T in series, primary winding of transformer TR, front contacts 11, 12 and 13 of relays 1S, 2S and 3S respectively and upper track rail to the (+) terminal of battery 1B. The 40 constants of the described energizing circuit for relay T are of such a value that sufficient current flows under the worst ballast conditions (maximum leakage between track rails) to maintain the contacts of relay T picked up. The best ballast conditions (minimum leakage between track rails) allows more current to flow over the above 45 described circuit including relay T which of course will maintain its contacts in their picked up positions.

- Any change in current flow over the above described circuit takes place through the primary winding of transformer TR but such a change due to a change in ballast conditions takes place quite slowly, so that there is no appreciable effect on the secondary winding of transformer TR due to such a change.
- Adjustable bias resistor BR is so adjusted that the grid of amplifier RC is normally sufficiently positive with respect to the filament that sufficient current flows from the (+) terminal of battery 2B, winding of relay 1S, plate filament circuit of the amplifier and resistor BR to the (-) terminal of battery 2B, for maintaining relay 1S in its picked up condition. Since slow changes in the track circuit current flow have no appreciable effect on the grid circuit of amplifier RC, this bias is maintained substantially constant so that relay 1S is not affected by such changes.
- Relay 2S is normally energized over a circuit extending from (+), front contact 14 of relay 1S and winding of relay 2S, to (-). Relay 3S is normally energized over a circuit extending from (+), front contact 15 of relay 2S and winding of relay 3S, to (-). With relays 1S, 2S and 3S picked up, resistances 1R, 2R and 3R are short circuited at front contacts 11, 12 and 13 so that they are not included in the circuit of the track relay.
- Track occupancy.*—When the illustrated track section is occupied the shunt across the track rails, due to the wheels and axles of the train, causes a sudden decrease in the current flowing through the windings of relay T. This sudden decrease in the current flow through the circuit including the primary winding of transformer TR, which is in series with the track relay windings, sets up a potential across the secondary winding of transformer TR in such a direction that the terminal connected to the grid of amplifier RC becomes more negative with respect to the filament to such an extent that the current flow through the plate circuit of the amplifier is reduced to a value which causes relay 1S to drop its contacts. Even though this potential is only momentary, relay 1S has time to drop its contacts and after the grid circuit returns to its normal state, with normal current flowing through the plate circuit of the vacuum tube, this current is insufficient to pick up relay 1S after it has dropped its contacts. This is due to the fact that the pick up current for the relay is considerably higher than its holding current.
- The dropping of front contact 11 removes the shunt from resistor 1R so that this resistor is inserted in the circuit of relay T. This further reduces the current flow through the windings of relay T so that it has less holding power than when the track rails were shunted by the train.
- Relay T may or may not release under this condition. If it does not release within a predetermined time, relay 2S will drop its contacts because front contact 14 of relay 1S deenergizes the winding of relay 2S. Relay 2S inserts resistance 2R in the circuit including relay T, by dropping its front contact 12. Relay T may or may not release under this condition. If it does not release after a predetermined interval of time, relay 3S is dropped because its energizing circuit is open at front contact 15 of relay 2S. Relay 3S then inserts resistance 3R in the track relay circuit by dropping its front contact 13.
- It will be understood that additional selecting relays may be provided if required, or if conditions are such that only one resistor 1R need be

inserted in the track relay circuit relays 2S and 3S may be omitted. When the selecting relays insert enough resistance in the circuit to drop relay T a stick circuit is provided to prevent other selector relays being dropped, which circuit extends from (+), back contact 16 of relay T, front contact 17 and winding of relay 2S, to (-). The stick circuit is also effective to stick relay 3S over a circuit including its front contact 18 and its winding, to (-).

It will thus be observed that relays 1S, 2S and 3S function to sequentially insert resistance in the circuit of the track relay until it releases, after which those relays (if any) which were not released will be stuck up through a back contact of the track relay. Since the stick circuits of the 2S and 3S relays are opened at their own front contacts, after the track relay is dropped the selector relays are not again picked up until the track becomes unoccupied as will be described.

Contact 21 of relay T and contact 31 of relay 1S in series may be used to control the signal circuits of signal SG or for any other purpose required by the usual practice in connection with track relay circuits. Front contact 22 of relay 3S is not shown connected to any circuit but this contact is included to indicate that another selecting relay can be provided when desired and connected to front contact 22 of relay 3S in a similar manner to which relay 3S is connected to front contact 15 of relay 2S.

Track unoccupancy.—When the train leaves the track section, the quick removal of the shunt across the track rails causes a sudden increase in current flow through the track circuit including the primary winding of transformer TR and the windings of the track relay in series. This sudden increase in current flow sets up a potential across the secondary winding of the transformer in an opposite sense to that previously explained so that the grid of amplifier RC becomes more positive with respect to the filament. This positive potential on the grid permits sufficient current to flow through the plate filament circuit for picking up relay 1S. Relay 1S removes resistor 1R from the track circuit and closes a circuit at its front contact 14 for picking up relay 2S. Relay 2S removes resistor 2R from the track circuit and closes a circuit at its front contact 15 for picking up relay 3S. Relay 3S removes resistor 3R from the track circuit. It will be understood that in the event that relay 3S or 2S were not dropped under the previous condition, then when the track becomes unoccupied relay 1S will pick up to remove resistor 1R which under this condition is the only one included.

With relays 1S, 2S and 3S picked up, the circuits are in condition for maximum current flow through the windings of relay T which causes this relay to be picked up. The circuits are now in normal condition.

It will be clear from the above description that this invention provides means whereby there is a positive discrimination between the track circuit conditions due to track occupancy and due to ballast leakage.

The above rather specific description of one form of the present invention has been given solely by way of illustration and is not intended in any manner whatsoever in a limiting sense. It will be obvious that the general principles herein disclosed may be embodied in many other organizations widely different from that illustrated without departing from the spirit of the invention as defined in the following claims.

What I claim is:—

1. In a track circuit, an insulated section of track, a source of current connected to said track, a track relay connected to said track and energized in slowly varying degrees in accordance with the slowly changing current values due to variations in ballast resistance, the entrance of a train into said section of track producing a rapid reduction in the current in the circuit of said relay, and means responsive only to said rapid reduction of current for sequentially inserting resistance units in the circuit of said relay until the resistance of the circuit including said relay has increased to a value where said relay releases. 5
2. In a track circuit, in combination with an insulated stretch of track, a source of current connected across one end of said track, a track relay connected across the other end of said track, an energizing circuit for said track relay including the track rails, a thermionic device, a transformer having its primary winding connected in series with said track relay and its secondary winding connected to the in-put circuit of said thermionic device, a control relay connected in the out-put circuit of said thermionic device, the resistance voltage drop across a portion of said energizing circuit supplying the in-put circuit of said thermionic device with a normal bias which maintains said control relay picked up irrespective of changes in the ballast condition of said stretch of track, and the voltage induced in the secondary winding of said transformer due to the entrance of a train into said stretch of track being sufficient to overcome said bias to cause said control relay to release, and means responsive to the release of said control relay for effecting a control of said track relay. 10
3. In a track circuit, in combination with an insulated stretch of track, a source of current connected across one end of said track, a track relay connected across the other end of said track, an energizing circuit for said track relay including the track rails, a thermionic device, a transformer having its primary winding connected in series with said relay and its secondary winding connected to the in-put circuit of said thermionic device, a control relay connected in the out-put circuit of said thermionic device, the resistance voltage drop across a portion of said energizing circuit supplying the in-put circuit of said thermionic device with a normal bias which maintains said control relay picked up irrespective of changes in the ballast condition of said stretch of track, the voltage induced in the secondary winding of said transformer due to the entrance of a train into said stretch of track sufficiently changing said bias to cause said control relay to release, and means controlled by said control relay for gradually inserting resistance in said track circuit until and only until said track relay is released. 15
4. In a track circuit, in combination with an insulated stretch of track, a source of current connected across one end of said track, a track relay connected across the other end of said track, an energizing circuit for said track relay including the track rails, a thermionic device, a transformer having its primary winding connected in series with said relay and its secondary winding connected to the in-put circuit of said thermionic device, a control relay connected to the out-put circuit of said thermionic device, the resistance voltage drop across a portion of
- said energizing circuit supplying the in-put circuit of said thermionic device with a normal bias which maintains said control relay picked up irrespective of changes in the ballast condition of said stretch of track, the voltage induced in the secondary winding of said transformer due to the entrance of a train into said stretch of track sufficiently changing said bias to cause said control relay to release, means controlled by said control relay for gradually inserting resistance in said track circuit until and only until said track relay is released, and means controlled by the exit of the train from said stretch of track for sufficiently changing said bias to cause said control relay to pick up. 20
5. A track circuit comprising an insulated track section; a track relay; a resistance normally excluded from the circuit of said track relay; discriminating means including a thermionic relay; means responsive to the occupancy of said section for operating said discriminating means; means responsive to the operation of said discriminating means for including said resistance in the circuit of said track relay; and means controlled by said track relay for controlling the amount of resistance included in its circuit. 25
6. In a track circuit, an insulated section of track, a source of current and a track relay connected to said track, a plurality of resistance units, slow-acting means for slowly and sequentially inserting said resistance units in series with said track relay until it releases, means including an impulse actuated device for starting the operation of said slow-acting means, and means controlled by the release of said track relay for stopping the operation of said slow-acting means. 30
7. In combination, a section of railway track, a source of current connected across the rails of said section, a relay receiving energy from the rails of said section and responsive to the steady value of current with which it is supplied, a transformer also receiving energy from the rails of said section, and means energized from said transformer and responsive to a change in the energization of the transformer occurring upon the entrance of a train into said section for decreasing the energization of said relay whereby said relay will release. 35
8. In combination, a section of railway track, a source of current connected across the rails of said section, a relay receiving energy from the rails of said section and responsive to the steady value of current with which it is supplied, a transformer having a winding included in the energizing circuit for said relay, and means energized from a winding of said transformer and responsive to a change in the energization of the transformer occurring upon the entrance of a train into said section for decreasing the energization of said relay whereby said relay will release. 40
9. In a track circuit for railroads, the combination with a section of railway track having a track relay and a source of uni-directional current connected thereto, an auxiliary relay separate from said track relay and effective when operated to decrease the current through said track relay and thereby cause release of its armature, and means including a transformer for causing operation of said auxiliary relay in response to the relatively quick change in the current in said track circuit caused by the entrance of a train into said section. 45
- 75

10. A track circuit for railroads comprising, a track relay, a source of unidirectional current for energizing said track relay, an inductive device, and means receiving energy from the track circuit through said inductive device and operating in response to the relatively high rate of change in the current in said track circuit produced by the entrance of a train upon said track circuit for decreasing the current through said track relay and thereby causing release of its armature.
11. In combination, a section of railway track, a source of current connected across the rails of

said section, a first relay receiving energy from the rails of said section and responsive to the steady value of current with which it is supplied, a second relay, means for controlling said second relay in accordance with the rate of change of current flow in said first relay when the value of current through said first relay is quickly decreased due to the entrance of a train into said section, and means controlled by said second relay for decreasing the energization of said first relay. 5
